UNITED STATES PATENT OFFICE.

ALBERT THOMAS LOCHNER, OF CHICAGO, ILLINOIS, ASSIGNOR TO WODACK ELECTRIC TOOL CORPORATION, OF CHICAGO, ILLINOIS, A CORPORATION OF ILLINOIS.

BRUSH-HOLDER.

1,395,440.

Specification of Letters Patent.

Patented Nov. 1, 1921.

Application filed July 17, 1919. Serial No. 311,494.

To all whom it may concern:

Be it known that I, ALBERT THOMAS LOCHNER, a citizen of the United States, residing at Chicago, in the county of Cook and State 5 of Illinois, have invented certain new and useful Improvements in Brush-Holders, of which the following is a specification.

My invention relates to holders for the brushes of electric motors. I have illustrated it in connection with a motor mounted in the cylindrical casing of an electric hand tool but it is applicable for use in connection with any type of motor.

One of the objects of my invention is to 15 construct a brush holder comprising as few parts as possible, very cheap to manufacture and simple and easy to assemble.

In the accompanying drawings, Figure 1 is a side view partly in section of the rear 20 end of an electric tool showing the application of a device according to my invention to an electric motor in the casing of the tool. Fig. 2 is a section on the line 2—2 of Fig. 1. Fig. 3 is a view looking downward at the 25 upper clip shown in Fig. 2, and Fig. 4 is a perspective view of the main metal member of the brush holder.

In the embodiment of my invention selected for illustration, the clip 10 comprising 30 the main element of my brush holder is formed of a single flat piece of sheet metal bent up as shown in Fig. 4 to provide at one end of said clip a rectangular transversely extending passageway 11 partly open on one 35 side, and at the opposite end a small upwardly projecting ear 12 terminating in a short hook-shaped extension 13.

Referring to Fig. 3, the metal clip is 40 mounted on a supporting member 14 by means of two machine screws 15 passing through suitable holes in said clip and supporting member. Insulating plates 17 and 18 separate the clip and the heads of the screws respectively, from the supporting 45 member, and fiber washers 19 insulate the portion of the screws passing through the supporting member 14. The contact brush 20 usually of carbon or other suitable material, slides in the passageway 11 and is 50 silently pressed against the commutator 21 (see Fig. 2) by a wire spring 22. The spring comprises a stationary finger 23 lying against the surface of the clip 10 and engaging the nut on one of the screws 15 so as

to be supported thereby as clearly indicated 55 in Fig. 2, a coil of several turns, of a height equal to that of the ear 12, and the finger 24 extending from the upper end of the coil into suitable engagement in a small notch in the butt of the brush. One of the screws 60 15 holding the clip 10 is equipped with two nuts and extends up from the surface of the clip far enough to allow the terminal contact of the flexible cable 25 reaching to the brush 20 and also the terminal contact of 65 the lead wire 26 supplying current to the armature, to be slipped over the screw on top of one of the nuts and firmly clamped in position by tightening the other nut on top of that. This screw, therefore, serves both as 70 a retaining member for the clip 10 and a binding post for the electrical connections, while the other screw fastens the clip and also provides a support or abutment for the stationary finger of the spring 22. 75

In assembling the brush holder in the casing 27 of the electrical tool illustrated, the supporting member 14 is in the shape of a ring having sliding engagement in the cylindrical portion 28 of the casing of the tool. 80 The ring 14 may be supported in operative position by any suitable means. I have illustrated a shoulder formed on the casing 27 against which the ring may be pushed and a resilient wire retaining ring 29 adapted to 85 be sprung into a suitable groove in the casing 27 and to hold the ring 14 in position. I have illustrated two brush holders supporting brushes which engage the commutator 21 at diametrically opposite points. It will 90 be obvious that there may be any desired number of brushes depending upon the type of motor used. My device is built up of a minimum number of parts which are quickly and easily formed from ordinary sheet metal 95 and spring wire.

While I have shown and described in detail a preferred embodiment of my invention, it should be clearly understood that the description is only for purpose of illustration and that many improvements and modifications will naturally occur to those skilled in the art. I aim in the subjoined claims to cover all such legitimate modifications and improvements. 100

I claim as my invention—

1. A brush holder for electrical machinery comprising, in combination, a one 105

- piece sheet metal clip having a transverse guideway at one end, a retaining member extending through said clip, a nut threaded on the end of said retaining member to 5 clamp said clip in position, and a spring having a stationary end engaging said nut so as to be supported thereby.
2. A brush holder comprising a plain strip of metal having one end bent repeatedly 10 at an angle to define a polygonal guideway transverse to the long dimension of the strip the leading edge of said bent end being on a wall of said guideway projecting toward the plain portion of the strip.
3. A brush holder comprising a plain strip of metal having one end bent repeatedly 15 at an angle so that the leading edge is on a portion projecting toward the unbent portion of the strip whereby to define a polygonal guideway transverse to the long dimension of the strip, and an ear at the 20 end of the strip opposite the guideway bent up out of the plane of the strip on the same side as the guideway.
4. In an electrical machine, a cylindrical casing, an annular supporting member in 25 said casing, said casing having a shoulder abutting said supporting member, an annular groove in said casing and a retaining member in said groove for holding said annular supporting member between itself and said shoulder, and brushes supported by said annular member.
5. In an electrical machine, in combination, 30 a brush, a sheet metal clip forming a guide for said brush, a supporting member, plates of insulating material on both sides of said supporting member, a retaining member passing through said insulating 35 plates, said support and said clip, and a spring having a stationary end, the projecting end of said retaining means being adapted to serve as a support therefor.
6. In an electrical machine, in combination, 40 a brush, a sheet metal clip bent to form a guide for said brush, a support, a plate of insulating material between said support and said clip, a second plate of insulating material on the opposite side of 45 said support, and a retaining member passing through said insulating plates, support and clip and projecting beyond the face of said clip to serve as a binding post for electrical connections.
7. In an electrical machine, a cylindrical casing, an annular supporting member in 50 said casing, said casing having a shoulder abutting said supporting member, an annular groove in said casing and a retaining member in said groove for holding said 55 annular supporting member between itself and said shoulder, a plurality of brush holders insulated from and supported by said annular supporting member, and 60 brushes in said holders.
8. A brush holder comprising a single strip of sheet metal substantially rectangular in shape and bent back upon itself at one end to provide a transverse guideway for a brush and having a member rising from the other end, and a spring mounted on said member having a free end engaging a brush operating in said guideway. 70
9. A brush holder comprising a single strip of sheet metal bent back upon itself at one end to provide a transverse guideway for a brush and provided at the other end with a member rising from the plane thereof, a spring mounted on said member and having a free end engaging a brush operating in said guideway, and a retaining member at the intermediate portion of the holder to hold the same in position. 75
10. A brush holder comprising a one-piece sheet metal clip of substantially rectangular shape conformed to provide at one end a transverse guideway for a brush and provided at the opposite end with a member rising from the plane thereof, a coiled spring mounted on said member and having a free end engaging a brush operating in said guideway, and a retaining member at the intermediate portion of the clip to hold 80 said clip in position, said retaining member constituting a support for the stationary finger of the coiled spring. 85
11. A brush holder comprising a single sheet metal strip bent to provide a brush guideway and having a member rising from the plane of the strip, a spring mounted on said member and having an end engaging a brush operating in said guideway, a binding post for electrical connections and a retaining means for securing the holder to a support comprising a bolt extending therethrough and constituting a support for the 90 spring. 100
12. In an electrical machine, the combination of a brush, a spring and a one-piece sheet metal plate bent to form a guideway for said brush and a support for said spring, and an attaching member extending through said plate to fasten the same to a support, the projecting end of said attaching member constituting an abutment for the stationary 105 finger of said spring. 110
13. In an electrical machine, the combination of a support, a brush, a sheet metal plate provided with a guideway adapted to support and guide said brush, and means for 115 yieldingly urging said brush into operating position together with means common to said plate and said means adapted to hold said plate rigidly to said support and to serve as a stationary supporting element for said 120 means. 125
14. A brush holder formed of a plain substantially rectangular strip of metal, the side edges of which are approximately straight, one end of the strip being bent over 130

to provide a four walled guideway extending from side to side of the strip.

15. A brush holder formed of a single strip of metal, the side edges of which are approximately straight and having at least one end cut approximately on a straight line, said strip being turned over at the end on

the main portion thereof to provide a substantially completely walled guideway extending from side to side of the strip. 10

In testimony whereof, I have hereunto set my hand.

ALBERT THOMAS LOCHNER.
